ATTORNEY

UNITED STATES PATENT OFFICE.

ARNOLD M. HOTELING, OF GERLAW, ILLINOIS.

FENCE FABRIC.

1,285,710.

Specification of Letters Patent. Patented Nov. 26, 1918.

Application filed October 9, 1917. Serial No. 195,621.

To all whom it may concern:

Be it known that I, ARNOLD M. HOTELING, a citizen of the United States, residing at Gerlaw, in the county of Warren and State 5 of Illinois, have invented certain new and useful Improvements in Fence Fabrics, of which the following is a specification.

This invention relates to fence fabric formed of woven wire, and aims primarily 10 to generally simplify and cheapen fence fabrics of this character as well as to increase the efficiency of the same.

A further object of the invention is to provide a fence fabric capable of being 15 easily constructed and at a great saving in material.

Still further objects reside in providing a fence fabric of that character wherein strands of angularly disposed flexible members 20 are employed, and which includes improved means for firmly locking the strands together at their point of crossing and in such manner as to permit of the fence fabric being readily flexed and which is 25 equipped with improved means for locking the ends of the transverse strands to the longitudinal strands so as to prevent movement of the transverse strands longitudinally of the fence fabric.

With these objects in view, together with others which will appear as the description 30 proceeds, the invention resides in the novel formation, combination, and arrangement of parts, all as will be described more fully 35 hereinafter, illustrated in the drawings, and particularly pointed out in the claim.

In the drawings:—

Figure 1 is a fragmentary view showing 40 a portion of a wire fabric fence constructed in accordance with the invention,

Fig. 2 is a view illustrating the manner in which the crossing strands are connected, the said view being taken upon the side of the fabric reverse from that shown in Fig. 1, 45 and

Fig. 3 is a sectional view taken on line 3—3 of Fig. 1.

Referring now more particularly to the drawings, 4 indicates the longitudinal 50 strands of the fence fabric and 5 the transverse strands. The outermost of the longitudinal strands 4 are provided at regular intervals with waved or twisted portions 6, while the intermediate strands are each provided at regular intervals with vertically 55 disposed loop portions 7. These loops are

inclined rearwardly slightly out of the vertical plane of the strands themselves, as shown in Fig. 3.

The transverse strands 5 are provided 60 with vertically disposed loops 8; the latter being arranged in spaced relation throughout substantially the entire length of the said transverse strands. The transverse strands immediately above the loop portions 65 therein are bent forwardly slightly so as to provide pockets or depressions to receive the upper parts of the loops 7 of the transverse strand. This construction limits the twisting of the longitudinal strands in one direction, 70 but permits of the ready rolling or folding of the fabric laterally.

In making up the fabric, the loops 7 and 8 of the longitudinal and transverse strands are looped together, thus holding the said 75 strands against movement relative to each other but permitting of the fabric being readily stretched or folded. The extremities of the transverse strands are bent in the direction of the longitudinal strands 4 80 and are then interwoven with the waved portions 6 of the said longitudinal strands. If desired, the longitudinal strands may remain straight throughout their lengths until the angularly bent ends of the transverse 85 strands 5 are applied thereto, whereupon the said ends and the longitudinal strands may be twisted together. By so locking the ends of the transverse strands, it is obvious that longitudinal movement of the same will be 90 prevented.

By constructing a fence in accordance with the foregoing, it is obvious that the fabric may be quickly formed without the use of intricate machinery, and at a great 95 saving of time and material. The intermediate longitudinal strands are looped with the transverse strands so as to permit a slight movement between the same, and only the extremities of the transverse strands are 100 rigidly secured.

While the present is a disclosure of what is believed to be the preferred embodiment of the invention, it is to be understood that the invention is not limited thereto, as 105 various changes in the minor details of construction, proportion, and arrangement of parts may be resorted to if desired without departing from the spirit of the invention as defined by the appended claim.

I claim:—

In a device of the class described, a fabric

comprising longitudinal and transverse strands, interlocked loops on said strands at their points of crossing, the loop of the longitudinal strand extending upwardly and 5 being bent rearwardly slightly, the loop on said transverse strand extending forwardly with a bent portion on said transverse strand extending above the loop thereof and receiving the upper part of the loop of said lon-

gitudinal strand, and the ends of said transverse strand being rigidly secured to the extreme longitudinal strands.

In testimony whereof I affix my signature in presence of two witnesses.

ARNOLD M. HOTELING.
